DISPENSING DEVICE

Fred K. Tarrant, Saratoga Springs, N. Y.

Application May 1, 1931. Serial No. 534,239

4 Claims. (Cl. 94—39)

This invention relates to dispensing devices and particularly for pouring hot or molten material, such as tar or asphalt.

It is common practice to fill the joints or cracks in pavements of concrete or like material with bituminous filler, such as asphalt. This is rendered difficult because of the nature of the material used and because the material must be poured in a hot or molten condition. Furthermore, it is difficult to direct the material into the cracks or crevices to be filled.

This invention has for its salient object to provide a device of the character described having means for directing the discharge nozzle and for guiding the material into the crack or crevice being filled.

Another object of the invention is to provide a device of the character described with simple and effective means for properly positioning the valve and for holding the discharge control valve open.

Further objects of the invention will appear from the following specification taken in connection with the drawing which forms a part of this application, and in which

Fig. 1 is a longitudinal sectional elevation of a device constructed in accordance with the invention;

Fig. 2 is a transverse sectional elevation taken substantially on line 2—2 and looking in the direction of the arrows;

Fig. 3 is a sectional elevation similar to Fig. 1, but partly broken away and showing the valve held in open position; and

Fig. 4 is a sectional elevation of the lower end of the receptacle and nozzle taken at right angles to Figs. 1 and 3.

The invention briefly described consists of a pouring pot or receptacle having a discharge nozzle at the lower end, a valve for controlling the passage of the material through the nozzle, means connected to the lower end of the receptacle and extending downwardly and beneath the discharge end of the nozzle for guiding the nozzle and also for guiding the material into a crack or crevice to be filled. Means is also provided for limiting the rotational or pivotal movement of the valve and for holding the valve in elevated or open position.

Further details of the invention will appear from the following description.

In the embodiment of the invention illustrated in the drawing there is shown a longitudinally tapered receptacle 10 having a boss 11 secured to the lower end thereof. A sleeve 12 extends

upwardly from the boss and has a plurality of openings 13 therethrough. The boss is provided with a valve seat 14 and with a downwardly extending sleeve 15 in which is threaded a sleeve 16 which in turn has threaded thereto an extension sleeve 17. The boss and the sleeves form a discharge nozzle for the receptacle.

The discharge of the material from the receptacle 10 through the nozzle is controlled by a valve 20 which is adapted to rest on the valve seat 14 and close the outlet through the nozzle. A valve rod 21 is connected to the valve 20 and extends upwardly through a transverse bar 22 which is connected to a bail 23 secured to the upper end of the receptacle. A handle 24 is formed on the upper end of the rod 21 and a fixed handle 25 is carried by the receptacle 10.

It is desirable to limit the pivotal or rotational movement of the valve rod 21 in the bar 22 since the valve 20 often fits the seat more closely in one position than in another. Therefore, when it has been found by experiment in what position the valve fits on the seat most efficiently means is provided for limiting the rotational movement of the rod and in the form of the invention shown this means consists of a rod 30 which is secured to the rod 21 at 31 and extends outwardly and downwardly over one edge of the bar 22. The rod 30 has formed thereon or secured thereto a longitudinally curved cross member 32 having ends 33 and 34 extending on opposite sides of the rod 30. After the rod 21 has been raised to open the valve it is swung or rotated in one direction or the other to position one of the ends 33 and 34 above the cross bar 22. The rod 21 can then be released and will be held in elevated position by one of the ends 33 and 34 which rests on the bar 22. The material will then be admitted to the sleeve 12 through the upper end thereof and through the openings 13 and will flow downwardly through the discharge nozzle.

In order to guide the nozzle along a crack or crevice or to guide the material into the crack a guiding pin 40 is carried by a lug 41 formed on the boss 11. The pin 40 extends downwardly and laterally beneath the lower end of the discharge nozzle, as shown at 42. The end 42 of the pin will be placed in the crack and will guide the nozzle along the crack and also as the material is discharged through the nozzle it will strike the pin and be guided thereby into the crack or crevice.

When the device is used the operator will grasp the bail 23 with one hand and the handle 25 with the other. The fingers of the hand which

grasps the bail 23 can engage the handle 24 and lift the rod 21 and valve 20. The end 42 of the pin will be placed in the crack and will be drawn along the crack and after the rod 21 has been elevated it can be supported in elevated position by turning it to a limited extent until one of the ends 33 or 34 of the member 32 is disposed above the cross bar 22.

Although one specific embodiment of the invention has been particularly shown and described, it will be understood that the invention is capable of modification and that changes in the construction and in the arrangement of the various cooperating parts may be made without departing from the spirit or scope of the invention, as expressed in the following claims.

What I claim is:

1. A dispensing device comprising a receptacle having a discharge nozzle at the bottom thereof, and a rod carried by said receptacle and extending downwardly therefrom and laterally beneath said nozzle for guiding the nozzle and material discharged therethrough.
2. A dispensing device comprising a receptacle having a discharge nozzle, a valve controlling the discharge therethrough, a rod connected to said valve, a cross bar at the upper end of the receptacle,

said rod extending through said bar, a member connected to said rod and extending parallel thereto and beyond one edge of said bar, and lugs on said member adapted to selectively rest on said bar and hold the rod elevated and the valve open.

3. A dispensing device comprising a receptacle having a discharge nozzle, a valve controlling the discharge of material therethrough, a rod connected to said valve, a transverse member through which the rod extends, and a member connected to said rod, extending over said transverse member and adapted to coact with said member to limit the rotary movement of said rod and valve.

4. A dispensing device comprising a receptacle having a discharge nozzle, a valve controlling the discharge of material therethrough, a rod connected to said valve, a transverse member through which the rod extends, a member connected to said rod, extending over said transverse member and adapted to coact with said member to limit the rotary movement of said rod and valve, and means on said member adapted to engage said transverse member to hold the rod elevated and the valve open.

FRED K. TARRANT.
